UNITED STATES PATENT OFFICE.

JOSEPH E. EVANS, OF BEDFORD, INDIANA, ASSIGNOR OF ONE-FOURTH TO CHARLES S. KNIGHT, OF CHICAGO, ILLINOIS.

SUSPENSION DEVICE FOR EQUALIZING THE STRAIN ON ELEVATOR CABLES.

Application filed November 17, 1924. Serial No. 750,337.

My invention relates to a device for equalizing the strain upon the different cables of a group of cables used for hoisting and lowering an elevator car such as those used in transferring passengers and freight from one floor of a building to another, especially a tall building where the lift is of considerable distance. In such cases the travel of the various cables, which all run over a common drum or hoisting pulley, usually differs slightly, owing to slight differences in the formation of the cable grooves, variations in stretch of the cables and other causes. In my Patent No. 1,429,150, I have described an equalizing device invented by me and designed to produce an equalization of the load of the car on the different cables, in which the elevator cables are connected to opposite ends of a group of horizontal supporting bars which spread the ends of the cables upon opposite sides of the plane of the periphery of the supporting pulley. In some installations it has been found that the necessary length of the equalizer bars and spread of the cable are such as to result in interference with stationary parts of the elevator framework, and one of the objects of my present invention is to produce an equalizing device which will enable the equalizer bars to be made shorter, and thus avoid the objection in question. Other and incidental objects and advantages relate to a suitable and desirable arrangement and construction of the members and parts of the device to attain the object first mentioned, all of which will be apparent from the description of my novel suspension device hereinafter given in detail, the essential elements of my invention being set forth in the appended claims.

In the drawings accompanying this specification, Figure 1 is a view of my device applied to an elevator installation of typical form; Fig. 2 is a side view of the device on a larger scale than Fig. 1; Fig. 3 is a view at right angles to the position of the parts in Fig. 2; Fig. 4 is a top plan view of the device; Fig. 5 is a horizontal section, immediately above the bottom plate of the device, showing the bottom plate in plan view; and Fig. 6 is a fragmentary side view illustrating a modified form of oscillatory member connected to a pair of the hoisting cables.

The same reference characters indicate the same parts in all the figures of the drawing.

In the ordinary and usual arrangement of parts of an elevator installation, as shown in Fig. 1, the hoisting cables A and A', connected at their inner and lower ends to the hoisting mechanism, track in alternate grooves formed in the periphery of the suspension pulley B at the top of the elevator shaft, thence, passing around a grooved idler pulley C, they track a second time over the pulley B in the intermediate grooves, the elevator car being secured to their outer ends.

My novel suspension device, designated as a whole by the reference letter D, comprises generally frame members secured to the car, a set of pulleys pivoted in the framework, a second set of pulleys connected to said first mentioned pulleys by an equalizing cable, a series of links axially connected to said second-mentioned pulleys and a set of equalizer bars (or equivalent oscillatory members) pivoted to said links and also connected at their opposite ends to the suspension cables. Describing these elements in detail, the frame members include a bottom plate 1 which may be a malleable casting, formed with downwardly extending bearing flanges 2 orificed to receive the pivot pins 3 upon which the pulleys 4 (two in number in the present instance) are mounted to rotate. The plate 1 is orificed to receive the clamping bolts 5 which at their top engage a composite top frame member consisting of two pairs of end bars having opposite outwardly-extending horizontal bottom portions 6 and vertical upwardly-extending top portions 6a, and a pair of side plates 7, the bars and plates being firmly secured together by rivets 8, or by other suitable means to form a rigid structure which is arranged on top of two beams 9-9 forming a part of the frame work of the elevator car. The bottom plate 1 is arranged below the beams 9-9, and the frame members are clamped securely to the beams by the clamping bolts 5 before mentioned. Manifestly the top frame members may be formed as integral parts of a single member, and the specific construction described may be varied as may be found convenient.

The outer ends of the suspension cables A, which in the device illustrated are six in

number, are pivotally connected in pairs, the members of which are marked A and A', to the opposite ends of three pairs of equalizer bars 10, each pair acting in unison and 5 functioning as a single bar. In the present instance the pivotal connection includes orificed pivot blocks 11 formed with trunnions 12 engaging pivot bearings in the corresponding ends of each pair of equalizer 10 bars 10. The cables are secured by means of sockets 13 to threaded bolts 14 which pass loosely through the orifices in the trunnions and which are each equipped with a pair of bearing nuts 15 engaging the under sides of 15 the pivot blocks and serving to sustain the load on the particular cable.

Each pair of equalizer bars is pivotally connected with a link which in the present instance is of composite construction and 20 consists of two members 16-16^a which function together as one. As will be seen by reference to Fig. 3 of the drawing the lower portions of each pair of link members diverge to form a fork arranged to straddle 25 a pulley 17 which is pivotally mounted between them, the three pulleys being engaged by a common equalizer cable 18 which is anchored at both ends to the bottom plate of the device and which is looped in alternation 30 over an outer upper pulley 17, a lower pulley 4, the intermediate upper pulley 17, the other lower pulley 4, and the other outer upper pulley 17.

Secured to the lower end of each pair of 35 link members 16-16^a I have provided a cable guard 19 which serves also as a stop member. This guard consists of a central orificed block portion riveted between the link members, and connected arcuate side 40 portions having opposite flanges arranged to overhang the pulleys 17. In case of breakage of the equalizer cable these guard and stop members would bring up against the side plate 7-7 of the upper portion of 45 the frame of the device, and sustain the weight of the car.

For the purpose of spacing and guiding the links in any variation of their position longitudinally I have provided cross pins 50 20 extending between the different sets of link members and secured to the side plates 7-7 of the top frame member.

The equalizer bars 10, as will be seen by reference to the drawings are set upon the 55 link sections 16-16^a at a slight angle with respect to radial planes of the suspension pulley, so that the ends of the suspension cables are disposed in staggered arrangement and track approximately tangentially into 60 the grooves of the suspension cables.

The lower pulleys 4, it will also be noted, are of such size and arranged at such angle to the pulleys 17 that the equalizer cable tracks tangentially between the grooves of 65 the different pulleys.

While I have found the equalizer bars above described a desirable and satisfactory means of pivotally connecting the cables to the equalizing pulleys, I may use, as an equivalent and also a desirable form of oscillatory members, pulleys pivoted to the links by which the equalizer pulleys are connected. I have shown such an arrangement in Fig. 6, the pair of cables A-A' associated with the connecting pulley 21 being connected to form 75 a loop 22 engaging such pulley.

I claim:

1. A suspension device for connecting a car to a plurality of cables comprising a set 80 of oscillatory members connected to spread pairs of cables, links pivoted at their upper ends to said oscillatory members, pulleys pivoted to the lower ends of said links, pulleys pivoted to the car, and an equalizer cable anchored at its ends to the car and engaging 85 said first mentioned and second mentioned pulleys in alternation.

2. A suspension device for connecting a car to a plurality of cables comprising a set 90 of equalizer bars connected at their opposite ends to spread pairs of cables, links pivoted at their upper ends to said bars, pulleys pivoted to the lower ends of said links, pulleys pivoted to the car, and an equalizer cable anchored at its ends to the car and engaging 95 said first mentioned and second mentioned pulleys in alternation.

3. In a device of the character described having a pair of equalizer bars connected at 100 their ends to a pair of suspension cables and having an equalizer pulley connected to the car, a connecting link pivoted between said bars at its upper end and forked at its lower end to straddle said pulley and form opposite pivotal supports therefor.

4. A suspension device according to claim 1 in which said links and the framework 110 of the device are provided with stop elements arranged to cooperate at an extended position in excess of the normal operative position of the link.

5. A suspension device according to claim 1 in which one or all of said links is equipped 115 with a cable guard overhanging its associated pulley, and the frame work of said device is formed with a stop member arranged to cooperate with said cable guard at an extended position in excess of the normal operative position of the link.

6. A device of the character described having 120 a set of oscillatory members connected to spread pairs of suspension cables and a corresponding set of equalizer pulleys connected to the car and a set of links pivoted to said oscillatory members and to said pulleys, the framework of said device including a pair of side plates forming guides for the 125 links.
